UNITED STATES PATENT OFFICE

WILLIAM WEIS, OF PERHAM, MINNESOTA

DESIGN FOR A CARD HOLDER FOR AUTOMOBILE RADIATOR FRONTS

Application filed June 13, 1932. Serial No. 44,066. Term of patent 7 years.

To all whom it may concern:

Be it known that I, WILLIAM WEIS, a citizen of the United States, residing at Perham, in the county of Otter Tail and State of Minnesota, have invented a new, original, and ornamental Design for a Card Holder for Automobile Radiator Fronts, of which the following is a specification, reference being had to the accompanying drawing, forming part thereof.

Fig. 1 is a front elevation showing my new design;

Fig. 2 is a section taken on the line 2—2 of Fig. 1; and

Fig. 3 is a section taken on the line 3—3 of Fig. 1.

The frame 4 is adapted to hold an ornamental card and the channel 5 is adapted to hold such objects as individual letter cards arranged to spell the name of a town or the like.

I claim:

The ornamental design for a card holder for automobile radiator fronts as shown and described.

WILLIAM WEIS.
